METHOD OF ASSEMBLING SUSPENDERS
AND SLIDESLyndon W. Joyce, Greensboro, N. C., assignor
to Joyce-Venning Manufacturing Co., Inc.,
Greensboro, N. C., a Corporation of DelawareApplication December 12, 1930
Serial No. 501,946

2 Claims. (Cl. 241—14)

This invention relates to the manufacture of suspenders and like articles, and proposes a method for assembling the operatively folded suspender web and the slide, as an alternative to the method disclosed in my pending application No. 5 494,378, filed November 8, 1930, patented October 13, 1931, No. 1,827,017, in which the web, pre-folded, is placed between the component slide parts, and by an act of pressure upon the whole, the slide parts are integrated into a slide with 10 the web folded therebetween.

The present invention utilizes a one-piece slide, that is to say, a slide in which the frame and middle bar are of one-piece or united, and the 15 novel method involves the step of opening the middle bar at some point to admit the assembled layers of the prefolded web, and the restoring of the middle bar to its normal closed position in the plane of the frame, so that the slide then 20 embraces the folds of the web in the normal and known manner.

The present invention is the converse of the 25 method followed in ordinary practice, for while it is usual to form the fold in the web by threading the web through a preformed slide, in the present invention the slide is folded about the prefolded web.

Other objects of the invention will appear as 30 the following description of illustrative and practical embodiments thereof proceed.

In the drawing in which the same characters of reference have been used throughout the several figures to designate identical parts:

Figures 1 to 4 inclusive, illustrate one form of 35 my invention. Figures 7 and 8 illustrate another modification. Figure 9 is a view which may be common to both forms of the invention.

Figure 1 is a perspective view of one form of slide;

Figures 2 and 3 are vertical elevations, partly 40 in section showing successive steps in one form of the method;

Figure 4 is a plan view of the web and slide parts in the positions shown in Figure 3;

Figures 5 and 6 are perspective views showing 45 other forms of slide amenable to the methods of assemblage proposed by the present invention;

Figures 7 and 8 are elevations showing the web 50 in section and illustrating two steps in a modified method;

Figure 9 is a perspective view showing the completed assembly.

Referring now in detail to the several figures, and first adverting to that form of the

invention shown in the group of Figures 1, 2, 3, 4 and 9, the numeral 1 represents a suspender slide made from a single piece of bent wire so as to constitute a substantially rectangular frame 2 and a middle bar 3. The middle bar may be 60 left with its abutting ends free or they may be joined by a ferrule 4 as shown in Figure 9 or by any other known and practical means of uniting.

Such slides as are shown in Figure 1 are old 65 in the art, but the usual method of inserting the web to form the sliding fold is to thread it through the spaces between the sides of the frame and middle bar. No one prior to the present invention has contemplated the use of 70 this slide or of any kindred slide in practicing a method by means of which the suspender web may be prefolded and the slide then applied operatively thereto without necessitating the threading of the web through the slide.

The operativeness of the present method is 75 predicated upon the provision of an open or discontinuous joint in the middle bar. Such a joint is shown at 5 in Figure 1, occurring at an intermediate point of the middle bar. By means of 80 this open joint, it is possible to divert or distort the respective portions 6 and 7 of the middle bar until they stand substantially perpendicular to the plane of the frame 2 as shown in Figure 2. A space is thus provided for the introduction of 85 the prefolded suspender web. Figure 2 shows that the portions 6 and 7 of the middle bar have been diverted by means of a spreader 8 having a linear dimension enabling it to fit widthwise within the frame and to press the portions 6 and 7 upwardly and apart until they stand perpendicular to the plane of the frame. The prefolded web is then inserted manually or otherwise in the space between the portions 6 and 7, which web 90 may rest upon the spreader 8 as the latter is retracted, until the web engages the frame 2 as shown in Figure 3. The material of which the slide is constructed may be assumed to have some elasticity so that as the spreader recedes, the portions 6 and 7 will return part-way toward their normal position as shown in Figure 3.

A die 9 is then applied to the obliquely disposed portions 6 and 7, pressing them into the plane of the slide and completing the latter. If it is desired to enclose and conceal the joint 5 within 95 in a ferrule, the ferrule blank 4 having its sides preferably slightly convergent, is placed upon the web in position to receive the free ends of the portions 6 and 7 as the latter are flattened by 100 the die, the sides of the ferrule blank being bent 105 in the die, the sides of the ferrule blank being bent 110

over the free ends of the portions 6 and 7 and crimped thereupon by the same act of pressure by which said portions are brought into the plane of the frame 2.

- 5 The assemblage of the web and slide by the method above described will be found more efficient in operation than an assemblage made by threading the web through the slide in the usual manner, since by the novel method it is possible
 10 to narrow the spaces between the frame side members and the middle bar, thus producing a superior degree of friction between the web and the slide.

A variant of the method is illustrated in Figures 7 and 8 in which the frame 2 comes to the assembling operation with the portions 6 and 7 already set at right angles to the plane of the frame. The spreader may be thus dispensed with. The folded web is laid down upon the frame and suitable dies 11 and 12 press the portions 6 and 7 into an oblique position as shown in Figure 8, whereupon the die 9 presses vertically upon the portions 6 and 7 flattening them into the plane of the frame 2, the dies 11 and 12 meanwhile receding.

In the carrying out of the novel method of this invention the nature of the slide is immaterial, providing that the middle bar is capable of opening at some point so as to admit the folded web to a position beneath said middle bar and above the frame. For example, instead of the slide being made as shown in Figure 1, it might be constructed as shown in Figure 6, the portions 13 and 14 overlapping, in parallel relation and each extending substantially the entire width of the frame. The portions 13 and 14 may be diverted in any desired manner into a position perpendicular to the frame to permit the insertion of the folded web, and they may then be restored to the plane of the slide by means such for instance, as those hereinbefore described.

Figure 5 shows another form of slide in which the ends of the wire are brought together in one of the sides of the frame as indicated at 15, and substantially united as for instance, by welding.

The assemblage of this slide with the folded web is accomplished in the same manner as in the modifications previously described.

While I have in the above description disclosed practical and illustrative embodiments of the invention, it is to be understood that the types of slide as well as the nature of the folded web may be varied at will, without transcending the scope of the invention as claimed.

What I claim is:

1. Method of assembling a suspender web and a suspender slide in operative relation comprising, folding the web so as to provide at least two layers at the point which is to be engaged by said slide, providing a slide having a frame for engaging one side of the folded web and a middle bar for engaging the other side, said middle bar being open at an intermediate point to permit entrance of the folded web into said slide; bending the portions of said middle bar away from one another to provide a space substantially as wide as the width of said slide, introducing said folded web through said opening into a position between said frame and said middle bar, arranging a ferrule blank on said web at the point to be overlain by the free ends of the portions of said middle bar, and closing said opening by bending said middle bar into substantially the same plane as said frame and closing said ferrule upon the adjacent ends of the portions of said middle bar.

2. Method of forming a draw loop of suspender webbing and assembling it in operative relation to a suspender slide without threading it between the middle and end bars of said slide, comprising folding the web so as to provide a loop, providing a slide having a substantially rectangular frame from the lateral portions of which the component part or parts of a divided middle bar rise at a substantial angle to the plane of said frame, introducing the two layers of folded webbing through the gap afforded by said divided middle bar, to a position against said frame, and closing said gap by bending the part or parts of said middle bar into substantially the plane of said frame.
